UNITED STATES PATENT OFFICE.

ISAAC LEVY, OF NEWPORT, RHODE ISLAND.

CORSET-BUSK.

SPECIFICATION forming part of Letters Patent No. 402,260, dated April 30, 1889.

Application filed July 26, 1888. Serial No. 281,065. (No model.)

To all whom it may concern:

Be it known that I, ISAAC LEVY, of Newport, in the county of Newport and State of Rhode Island, have invented a new and Improved 5 Corset-Busk, of which the following is a full, clear, and exact description.

This invention relates to corset busks or stays, and has for its object to provide a light corset-busk which will be strong, stiff, and 10 yielding to the motions of the body and will retain its shape.

The invention consists in a corset-busk, and in details of construction thereof, constructed and arranged as hereinafter described and 15 claimed.

Reference is to be had to the accompanying drawings, forming a part of this specification, in which similar figures of reference indicate corresponding parts in all the views.

20 Figure 1 illustrates a pair of corset-busks constructed in accordance with this invention and connected together by clasps. Fig. 2 is a view of a corset-busk constructed in accordance with this invention with a broad lower 25 end to form a spoon or busk and the upper portion broken away. Fig. 3 is a detail view showing a modified form of clasp for the busks. Fig. 4 is a detail showing another form with stud. Fig. 5 is a view of a portion of a pair 30 of busks, showing another modified form of clasp. Fig. 6 is a view of a portion of the wires bent to form a clasp and stud. Fig. 7 is a modification showing one means of fastening wires together, and Fig. 8 shows another 35 way of securing wires together.

In constructing a corset-busk according to this invention, it is designed to form the busk of a number of wires connected together, so as to constitute a light stiff busk which will 40 take the place of other forms of busk in one piece—such as those made of flat strips of steel, whalebone, or other material—and which will be flexible laterally as well as longitudinally to adapt it to the movements of the body. To this end I construct a busk with a 45 number of flexible steel wires, 1, connected together by metallic cross strips or braces 2, secured thereto in any suitable manner, either by bending the strips 2 about the wires 1, as 50 shown in Figs. 1, 2, 4, and 5, and securing them by solder, 3, or else by clamping the wires be-

tween a folded strip, 2, without solder, as shown in Fig. 7, or bending the ends of a strip 2 over the outside wires and securing the wires to the strip and together by solder 3, as shown 55 in Fig. 8.

While the wires 1 have a certain amount of elasticity, there is a limit thereto in which they will return to their straight position. In order, therefore, to render the busk more flexible and at the same time to preserve its stiffness, the wires 1 are formed with a number of coils, 4, at intervals, thereby forming a stiff and powerful spring, and so constructed as to leave the back of the busk smooth and 60 avoid any projections or unevenness which would be liable to press into the body of the wearer. By means of a busk or corset stay constructed as above described a busk is provided which will yield in every direction to 65 the movements of the body, will keep its shape and stiffness, and will not be liable to break.

In case one of the wires should break, the broken portion would be of such a short length between the braces 2 as to avoid any danger 70 of injuring the wearer, and may be taken out without affecting the use of the rest of that or the other wires. Each wire being independent of the others and acting as a spring 75 by itself, it does not materially affect the working of the broken one or the others should a section between the braces break out.

There may be any number of wires 1, and they may be independent or formed of a single wire with the folded ends secured by the 80 braces 2 at the ends of the busk. Any form of clasp and stud may be used with the busks, either in the form as shown at 5 in Fig. 1, or a clasp with folded portion 6 and stud 7, between which wires 1 may be clamped, as shown 85 in Fig. 3. In Fig. 5 is shown another form, in which a wire 1 in one busk is formed with a hook, 8, and a wire 1 in another busk is formed with a U-shaped clasp, 9, to engage 90 the same. In Fig. 6 is another form, in which one of the wires is formed with a folded projection, 10, and a cap or head, 10', soldered thereto and forming a stud, and a V-shaped portion, 11, on another wire, forming a clasp. By means of this construction a simple clasp 95 is provided, and separate metallic pieces attached by stamping or soldering done away 100

with. The latter form of clasp also allows plenty of play for the movements of the body. The busk may be made with the broad lower end, 12, as shown in Fig. 2, to give a strong firm bearing to the lower end of the corset, and the side stays may be made of any number of wires desired to give a broad surface to the busk.

I do not intend to limit myself to any form of brace or cross-strip for connecting the wires together, nor to any particular form of clasp or means for attaching the braces and clasps to the wires.

The wires 1 of the busk may be formed with 15 as many coils 4 as is deemed necessary to give flexibility and at the same time stiffness to the busk, and the coils 4 may be arranged on the busk in any convenient desirable position.

Having thus described my invention, what 20 I claim as new, and desire to secure by Letters Patent, is—

1. A corset-busk consisting of a series of longitudinal wires connected together at in-

tervals in their length by strips or braces, each wire being formed with spring-coils, substantially as described.

2. A corset-busk consisting of a series of longitudinal wires, 1, formed with spring-coils 4 and secured together by the clips or braces 2, and having a broad lower end, 12, substantially as described.

3. The combination of two corset-busks, each consisting of a series of longitudinal wires formed with spring-coils and secured together at intervals, one of the said busks having one of its wires bent to form a hook projecting from the face of the busk and the other busk having one of its wires bent to form a loop projecting from the edge of the busk, substantially as herein shown and described.

ISAAC LEVY.
